[57] CLAIM

The ornamental design for a club head, as shown.

DESCRIPTION

FIG. 1 is a rear elevation view of a golf club head showing my new design;

FIG. 2 is a front elevation view thereof;

FIG. 3 is a top plan view thereof;

FIG. 4 is a bottom plan view thereof;

FIG. 5 is an end elevation view taken from the right of FIG. 1; and,

FIG. 6 is an end elevation view taken from the left of FIG. 1.

The characteristic feature of my design resides in the pattern of hexagonal units shown on the rear surface of the club head in FIG. 1.

The broken line showing grooves on the striking face is for illustrative purposes only and forms no part of the claimed design.
